UNITED STATES PATENT OFFICE.

WILLIAM M. SAUNDERS, OF WATERBURY, CONNECTICUT, ASSIGNOR TO THE MATTATUCK MANUFACTURING COMPANY, OF WATERBURY, CONNECTICUT, A CORPORATION OF CONNECTICUT.

MUSIC-ROLL END.

Application filed March 2, 1925. Serial No. 12,620.

To all whom it may concern:

Be it known that I, WILLIAM M. SAUNDERS, a citizen of the United States, residing at Waterbury, county of New Haven, State 5 of Connecticut, have invented a certain new and useful Improvement in Music-Roll Ends, of which the following is a full, clear, and exact description.

My invention relates to music roll ends 10 and has for its object to provide a new and improved sheet metal music roll end which shall be strong and accurate and inexpensive in manufacture.

The following is a description of an embodiment of my invention reference being had to the accompanying drawing, in which:

Figure 1 is a side elevation of a music roll, partly in section, embodying my invention;

Fig. 2 is a right hand end view of the same;

Fig. 3 is a left hand end view of the same; and

Fig. 4 is a section on the line 4—4, Fig. 1.

Referring more particularly to the drawing, 2 is a sheet of perforated paper upon a tubular core 4 of pasteboard or the like. 6 is a flanged member having a curled edge 8 and a tubular projection 10 drawn from its center so as to produce a shank entering the core of the roll. Secured to the flanged member is a cup-shaped shell 12 having a flange 14 which is spot-welded to the flange of the flanged member. The right hand roll end is provided with a recess 16 forming a bearing for a fixed spindle, while the left hand roll end is provided with a slot 18 adapted to receive the flattened end of a driving spindle.

These roll ends can be made up from the sheet metal by means of suitable dies and when so made the shanks 10 being integral with the flanges will eliminate the possibility of the roll running out of true and furthermore the flange of the flanged member being forced up against the end of the core secures a true riding edge for the paper to curl against. Furthermore, any blow 50 upon the end of the roll will be transmitted to the flange of the flanged member along a line parallel with the axis of the roll so that the force of the blow will be resisted by a direct thrust, thus reducing the liability of

the roll end to become distorted by an end- 55 wise blow. The flange of the flanged member is reenforced by radial corrugations 20 which together with the curled edge 8 enable the flange member to be made of light material and still have the necessary strength. By 60 making the shank integral with the flange of the flanged member I am enabled to make the cup portion 12 of metal of increased gauge if desired, and also insure true alinement of the shank and flange of the flanged member. 65

As will be evident to those skilled in the art, my invention permits of various modifications without departing from the spirit thereof or the scope of the appended 70 claims.

What I claim is:

1. In a music roll end a sheet metal flange having a hollow portion protruding therefrom and integral therewith and a cylindrical shell extending in the opposite direction from said hollow portion and constituting a second protruding portion and having a rim secured to said flange member adjacent to the wall of said hollow protruding 75 portion, one of said oppositely extending portions having a spindle engaging portion.

2. In a music roll end a sheet metal flange having a hollow portion protruding therefrom and integral therewith, and a cylindrical shell extending in the opposite direction from said hollow portion and constituting a second protruding portion and having a rim secured to said flange member adjacent to the wall of said hollow protruding 80 portion, one of said oppositely extending 85 portions having a spindle engaging portion.

3. In a music roll end a sheet metal flange having a cylindrical hollow shank protruding therefrom and integral therewith, and a cup-shaped shell extending in the opposite direction from said shank and constituting a second protruding portion and having a rim secured to said flange member adjacent 90 to the wall of said hollow protruding portion, said shell being provided with a slot 95 for a driving spindle.

In testimony whereof, I have signed my name to this specification this 27th day of February, 1925.

WILLIAM M. SAUNDERS.
